JACOB B. McCLEARY, OF CUMBERLAND, MARYLAND, AND WILLIAM D. HERSHBERGER,
OF PATTERSONS CREEK, WEST VIRGINIA.

RAILWAY ANTICREEPER.

Application filed January 18, 1926. Serial No. 82,004.

The invention relates to devices for use in connection with railway tracks, known in the art as anticreepers, the purpose of which is to prevent the rails from moving lengthwise in the direction of movement of the train.

The object of the present invention is to provide a simple form of anticreeping device, which may be manufactured at small 10 cost, which is readily applied to the track-way and which is positive in its effect, serving to securely lock the rail against creeping, the locking effect increasing as the creeping tendency is increased.

15 The invention will be more readily understood by reference to the accompanying drawing showing an illustrative embodiment of the invention.

In the drawings:

20 Figure 1 is a side view showing a portion of track including the rail and a tie, to which the improved anticreeper is applied.

Figure 2 is a sectional view through a rail to which the anticreeper is applied, the anti- 25 creeper being shown in end elevation.

Referring to the drawing, the reference numeral 10 denotes a portion of a rail which has a tendency to creep to the left in the direction of the arrow. The rail 10 is secured to the tie 11 by means of the usual 30 spikes 12.

In order to firmly lock the rail to the tie and to prevent creeping the improved anti-creeping device is applied to the rail adjacent each tie and on the side of the tie from which the creeping force is exerted. If in any case the rail has a tendency to creep in both directions under different 35 forces one of the anticreepers should be supplied at each side of the tie.

As shown, the anticreeper consists of an underlying member 13 which fits under the rail and is provided at one end with a flange 14 against which one edge of the lower base 45 15 of the rail is adapted to fit, a hook shaped projection 16 being provided at its other end in order to fit over base 17 of the rail.

Extending at an angle from the base portion 13 of the anticreeper, and intermediate the flange 14 and the hook 16, is an arm 18 at the outer end of which is an enlarged tie engaging portion 19. The portion 19 is convexly curved in the direction which faces vertical side 20 of the tie 11 and the arm 18

may be curved to correspond roughly with the curvature of the tie engaging portion.

The tie engaging portion 19 may be formed integral with the arm 18 or it may be formed by welding or otherwise securing thereto a pair of wing portions 21 which 60 serve to give a greater tie engaging surface.

In assembling, the hook of the anticreeper is slipped onto the base of the rail before the rail is laid, the lug 14 fitting against the other side of the base. The anticreeper is 65 then slid to the proper position adjacent one of the ties and the rail laid in place. The anticreeper is so placed that the member 19 engages the vertical side of the tie. The hook 16 and the lug 14 engage the base of 70 the rail sufficiently tightly to prevent their accidental removal.

The operation of the device will be evident from the foregoing description. When a force is applied to the rail 10 which would 75 tend to move it in the direction of the arrow the tie engaging portion 19 of the anti-creep 80 er is forced hard against the vertical side 20 of the tie 11. By reason of the curved surface of this member the entire 85 anticreeper is moved from the dotted position shown in Figure 1 to the full line position. This causes the rail engaging portion 90 of the anticreeper to bite the base of the rail and thereby lock the same against movement 95 in the direction of the arrow. It will be seen that the greater the force applied to the rail tending to cause it to creep in the direction of the arrow the greater will be the torsion grip action of the tie engaging member, which will be transmitted with increased 100 force by reason of the leverage afforded by the arm 18, to the rail engaging member, so that the locking action is proportional to the force tending to cause creeping.

The invention has been described in detail for the purpose of illustration, but it will be evident that variations may be resorted to within the scope of the appended claims.

What we claim is:—

1. In combination with a rail and tie, an 100 anticreeping device adapted to be applied to the rail on the side of the tie from which a creeping force is exerted, said device comprising a flat horizontally extending rail- 105 gripping portion adapted to underlie the rail, said gripping portion having a flange and a hook-shaped member at the ends there-

- of adapted to engage the base of the rail, and an integral arm intermediate the flange and the hook, extending directly forwardly and downwardly from said rail gripping portion, said arm being provided with an enlarged convexly curved tie-engaging portion adapted to engage the vertical side of the adjacent tie when a creeping force is applied to the rail, whereby a torsion grip is produced tending to rotate said anticreeper about a horizontal axis to thereby lock the rail-engaging member to the rail with a force which increases with the creeping force:
15. A one-piece railway anticreeper comprising a rail-gripping portion adapted to underlie the rail and having an abutment at one end and a rail-engaging hook at the other end, an integral arm intermediate said hook and said abutment, said arm extending directly forward and at an angle downwardly in a vertical plane from said rail-gripping portion, the arm having an en-

larged tie-engaging portion, convexly curved toward the vertical side of the adjacent tie, and adapted to cause the anticreeper to rotate about a horizontal axis to exert a torsion grip, tending to increase the locking action of the rail-gripping member as the creeping tendency of the rail is increased. 25

30. 3. A one-piece railway anticreeper comprising a rail-gripping portion adapted to underlie the rail and secured at its ends to the base of the rail, an integral arm intermediate the ends of said rail-gripping member, extending directly forwardly, and at an angle downwardly from said rail-gripping portion, said arm terminating in a tie engaging portion, adapted to cause the anticreeper to rotate about a horizontal axis 35 to exert a torsion grip tending to increase the locking action of the rail-gripping member as the creeping tendency of the rail is increased. 40
